OSCILLATOR CONTROL

Harold W. Lord, Schenectady, N. Y., assignor to
General Electric Company, a corporation of
New York

Application March 16, 1936, Serial No. 69,243

18 Claims. (Cl. 171—97)

My invention relates to electric valve circuits, and more particularly to electric circuits employing electronic discharge devices of the gaseous type for controlling electric valve oscillators.

5 Heretofore there have been devised various arrangements for controlling electric valve oscillators. Many of the prior art arrangements for controlling electric valve oscillators have employed electromagnetic devices, electric valves 10 of the high vacuum type or electromagnetic devices controlled by auxiliary electric valves. A distinct disadvantage has been encountered in the use of prior art arrangements for controlling electric valve oscillators. In many of the prior art 15 circuits the auxiliary control apparatus has been subjected to voltages of an order of magnitude substantially equal to the voltage of the main electric valve oscillator. There has been evidenced a decided need for an arrangement where- 20 by electric valve oscillators may be satisfactorily controlled by electronic discharge devices of the gaseous type without employing expensive and complicated auxiliary equipment.

An object of my invention is to provide an improved circuit for controlling an electric valve oscillator which obviates the above mentioned difficulties.

Another object of my invention is to provide a new and improved circuit employing an electronic discharge device of the gaseous type for controlling directly an electric valve oscillator.

A further object of my invention is to provide a circuit for periodically controlling an electric valve oscillator by means of a periodic electric 35 timing circuit and an electronic discharge device of the gaseous type.

In accordance with the illustrated embodiments of my invention, I provide an arrangement for directly controlling an electric valve oscillator by 40 means of an electronic discharge device of the gaseous type which is connected across an impedance element in the oscillator circuit. When the electronic discharge device is conductive so that the impedance element is shunted, the oscillator is started and when the discharge device is rendered non-conductive the oscillator is stopped.

For a better understanding of my invention, together with other and further objects thereof, reference may be had to the following description 45 taken in connection with the accompanying drawing, and its scope will be pointed out in the appended claims.

In the drawing, Fig. 1 diagrammatically represents an embodiment of my invention for controlling an electric valve oscillator; and Fig. 2

diagrammatically illustrates my invention applied to an arrangement for controlling an electric valve oscillator circuit of the self-rectifying type.

Referring to Fig. 1 of the accompanying drawing, my invention is diagrammatically shown in 5 an arrangement for controlling the energization of an electric valve oscillator. An electronic discharge device 1 of the gaseous type, having an anode 2, a cathode 3 and a control member 4, is provided to control any suitable electric valve oscillator such as the electric valve oscillator 5. By the use of the term "electronic discharge device of the gaseous type", I intend to include electric valves of the gaseous type or electric valves of the vapor type such as those employing mercury 15 vapor. The oscillator 5 as shown comprises an electric valve 6 having an anode 7, a cathode 8 and a control member 9 which cooperates with a parallel connected inductance 10 and a capacitance 12 to generate relatively high frequency 20 electrical oscillations. The inductance 10 is provided with a tap connection 11 which serves as a supply connection for the oscillator circuit 5. A self-biasing control circuit for the control member 9 of electric valve 6 includes a capacitance 25 13 and a resistance 14. A current limiting resistance 15 is connected to the capacitance 13 and resistance 14 by a conductor 16; and an impedance element, such as a resistance 17, is connected in the anode-cathode circuit of electric 30 valve 6. The cathode 8 of electric valve 6 is connected to the anode 2 of the electronic discharge device 1 through conductors 18, a secondary winding 19 of a cathode heating transformer 20 and a conductor 21. The cathode 3 of the electronic dis- 35 charge device 1 is connected to the resistances 15 and 17 through a secondary winding 23 of a cathode heating transformer 22, and through conductors 24, 25 and 26. To control the energization of the gaseous discharge device 1, I employ a 40 circuit 27 connected across the cathode 3 and the control member 4 through a suitable resistance 28.

The load circuit 29 is energized from the winding 30 which is inductively associated with the inductance 10 and impresses a relatively high 45 frequency potential on the load circuit 29. By controlling the energization of the electronic discharge device 1, the oscillator 5 is controlled thereby effecting control of the circuit 29.

To supply a pulsating unidirectional potential 50 to the oscillator 5, I employ any suitable rectifying means such as the electric valve bi-phase rectifier 32 energized from any suitable relatively low frequency alternating current circuit 31. The rectifier 32 includes electric valves 33 and 34 55

which are energized from the alternating current circuit 31 through a transformer 35 having a secondary winding 36 and which is provided with a mid-tap connection 37. The cathodes of electric valves 33 and 34 are connected through a secondary winding 39 of a cathode heating transformer 38, and conductors 40 and 41 to the tap 11 of inductance 10, and a conductor 42 is employed to connect the oscillator 5 to the rectifier 32 and serves as the negative side of the direct current source 43, while the conductor 40 serves as the positive side.

Connected across the source of pulsating direct current 43, I employ a capacitance 44 which serves to by-pass the high frequency oscillations. To discharge the capacitance 44 when the oscillator 5 is not operating, a resistance 45 of relatively high value is connected in parallel with the capacitance 44 and is also connected across the direct current source 43. The lower terminals of the capacitance 44 and the resistance 45 are connected to the oscillator 5 and the electronic discharge device 1 by a conductor 46.

In explaining the operation of the embodiment 25 of my invention diagrammatically shown in Fig. 1, let it be assumed that the rectifier 32 is supplying a substantially unfiltered unidirectional pulsating potential to the circuit 43. Since the capacitance 44 and resistance 45 are not designed 30 to smooth the pulsating potential of the rectifier, the pulsating output potential of the rectifier 32 will be impressed upon the oscillator 5. If the electronic discharge device 1 is maintained non-conductive by impressing a suitable negative potential 35 on the control member 4 by means of circuit 27, the oscillator 5 will not be put into oscillation. However, if the device 1 is rendered conductive by a suitable potential being impressed on the control member 4 through circuit 27, the 40 device 1 will be rendered conductive thereby shunting the resistance 17. Upon short circuiting the resistance 17 through the device 1, the bias on the control member 9 of electric valve 6 will be reduced sufficiently to permit the circuit 45 5 to oscillate to introduce a high frequency modulated potential in the load circuit 29. So long as the device 1 is conductive, the oscillator 5 will oscillate in the manner well understood by those skilled in the art.

50 The electrical valves 33 and 34 will be rendered conductive alternately to effect rectification of the low frequency alternating current of source 31 to supply a pulsating unidirectional current to circuit 43. The path of the rectified low frequency current comprises conductor 40, conductor 41, inductance 10, electric valve 6, conductors 18, secondary winding 19 of transformer 20, conductor 21, resistance 17, conductors 26, 46 and 42. When the electronic discharge device 1 is conductive it, of course, will shunt the resistance 17 causing the rectified low frequency current to flow through secondary winding 23 of transformer 22 and conductors 24, 25, 46 and 42. The circuit for the high frequency electrical oscillations generated by the oscillator circuit 5 comprises inductance 10, capacitance 12, electric valve 6, conductors 18, electric discharge device 1, secondary winding 23 of transformer 22, conductors 24, 25 and 46, and capacitance 44.

70 Near the end of each impulse of unidirectional potential impressed on the oscillator 5 from the alternating current circuit 31 by the rectifier 32, the self-biasing circuit comprising the resistance 14 and the capacitance 13 causes the circuit 5 to stop oscillation due to the negative bias poten-

tial impressed on the control member 9 of electric valve 6. The deionization time of the electronic discharge device 1 is not short enough to permit the control member 4 to gain control of the device between cycles of the high frequency oscillations. But the self-biasing action of the capacitance 13 and the resistance 14 causes the circuit 5 to stop oscillating and interrupts the flow of current near the end of each half cycle of alternating potential of source 31 to permit the 10 electronic discharge device 1 to become non-conductive if a suitable negative potential is impressed on the control member 4 by the circuit 27. If the electronic discharge device 1 is not conductive, the negative bias voltage impressed on the control member 9 of valve 6 will be maintained at this increased value by the subsequent unidirectional impulses, thereby maintaining electric valve 6 non-conductive and preventing the circuit 5 from oscillating. This increase in the bias voltage is occasioned by the rectified low frequency current flowing through the resistance 17. When the device 1 is rendered conductive, the negative bias voltage impressed on the control member 9 of valve 6 is decreased to a value which permits the circuit 5 to oscillate.

Since the oscillator 5 may be controlled by means of the electronic discharge device 1 of the gaseous type, it should be understood that by controlling the conductivity of the device 1 through circuit 27, the energization of the load circuit 29 may also be controlled. During the time the device 1 is conductive, the oscillator 5 will impress a train of high frequency electrical impulses on the load circuit 29.

Referring now to Fig. 2 of the accompanying drawing in which a modification of my invention is diagrammatically shown in an arrangement for controlling an oscillator of the self-rectifying type. An electronic discharge device 40 41 of the gaseous type having an anode 48, a cathode 49 and a control member 50 is employed to control an oscillator 51 of the self-rectifying type, which in turn is employed to energize a load circuit 52.

The oscillator 51 may be energized from any relatively low frequency alternating current circuit 53 through a transformer 54 having a secondary winding 55 provided with a mid-tap connection 56. Electric valves 57 and 58 having anodes 59 and 60, cathodes 61 and 62 and control members 63 and 64, respectively, are employed in the oscillator circuit 51 to rectify the alternating potential of source 53 and also serve the purpose of generating the high frequency oscillations. A multi-winding high frequency transformer 65 having primary windings 66 and 67 and secondary windings 68 and 69 is used to impress the voltage appearing across the secondary winding 55 of transformer 54 on anodes 60 59 and 60 of electric valves 57 and 58, respectively. Transformer 65 also serves the purpose of supplying the necessary inductive reactance for the oscillator 51. Capacitances 70 and 70' are connected between the upper and 65 lower terminals, respectively, and the mid-connection 56 of secondary winding 55 of transformer 54. The anodes 59 and 60 of electric valves 57 and 58, respectively, are connected to the secondary winding 55 of transformer 54 through conductors 71 and 72, windings 66 and 67 and conductors 73 and 74 respectively. A capacitance 75 is connected across the secondary winding 68 of transformer 65 and serves as a part of the high frequency oscillation circuit.

A self-biasing circuit for energizing the control members 63 and 64 of electric valves 57 and 58 comprises a capacitance 76 and a resistance 77. Current limiting resistances 78 and 79 are connected in series with control members 64 and 63 of electric valves 58 and 57, respectively, and also serve to suppress parasitic oscillations.

To control the oscillator 51 and to render the electronic discharge device 47 non-conductive at the end of each half cycle of rectified potential of the alternating current circuit 53, I employ a circuit 80 comprising an impedance element, such as a resistance 81, and a resistance 82 and a capacitance 83 connected across the resistance 82. The resistance 81 is connected to the anode 48 of electronic device 47 through a conductor 84, and to the cathode 49 through the parallel circuit comprising resistance 82 and capacitance 83, conductor 85 and a secondary winding 87 of a cathode heating transformer 86. The anode 48 of vapor electric valve 47 is connected to the cathodes 61 and 62 of valves 57 and 58, respectively, through the secondary winding 88 of a cathode heating transformer 88 and conductors 89 and 91. The mid-connection 56 of secondary winding 85 is connected to the left-hand terminals of resistances 81 and 82 and capacitance 83 through conductors 92 and 93. Conductor 94 is employed to connect the lower terminal of resistance 77 in the self-biasing circuit to a mid-connection of secondary winding 88 of the high frequency transformer 85.

The timing circuit 95 may be used to control periodically the conductivity of the electronic discharge device 47 and thereby to effect control of the oscillator 51. By means of the timing circuit 95, a periodic timing potential of suitable wave form is impressed across the control member 50 and the cathode 49 of valve 47 through a conductor 96 and a conductor 97, conductor 93, resistance 82, conductor 85 and secondary winding 87. The timing circuit 95 is disclosed and claimed in my copending applications Serial No. 585,292 and Serial No. 69,244 filed January 7, 1932, and March 16, 1936, respectively, and both of which are assigned to the assignee of the present application. The timing circuit 95 diagrammatically illustrated in Fig. 2 of the drawing comprises a source of direct current 98, a voltage divider 99 including resistances 100 and 101, the former having an adjustable contact 102, a capacitance 103, a resistance 104, an auxiliary discharge circuit comprising a serially-connected resistance 105 and a capacitance 106 and a means for periodically discharging capacitance 103 such as a vapor electric discharge valve 107 having a control member 108. An inductive element 109 is connected in series with valve 107 to assist in the control of the valve 107, and a transformer 110, preferably of the type designed to supply a voltage of peaked wave form, is connected in the control member circuit for electric valve 107 to render the valve 107 conductive precisely at predetermined times. The transformer 110 may be energized from the alternating current source 53 or other suitable source to control the period of the periodic potential of circuit 95, thereby effecting co-ordination between the control of electronic device 47 and the alternating potential of source 53. A switch 112, having stationary contacts 113 and 114 connected to the terminals of capacitance 106 and a movable member 115, is employed to obtain an adjustment in the ratio of the period of non-conduction to the period of conduction of electronic device 47. When the

movable member 115 of switch 112 is in contact with the stationary member 113, the periodic peaked potential impressed on the control member 50 of device 47 is of relatively short duration effecting thereby a high ratio of the period of non-conduction to the period of conduction. Whereas, when the movable member 115 is connected to contact 114 the periodic peaked potential is of longer duration to effect thereby an increase in the period of conduction of device 47 and a decrease in the ratio of the period of non-conduction to the period of conduction.

The operation of the embodiment of my invention diagrammatically shown in Fig. 2 may be explained by considering the arrangement when the oscillator 51 is being controlled by the electronic discharge device 47 to supply trains of high frequency oscillations to the load circuit 52. In the manner well understood by those skilled in the art, the electric valves 57 and 58 will operate alternately to rectify the alternating potential of the relatively low frequency alternating current source 53 and at the same time will generate relatively high frequency modulated oscillations which are impressed on the load circuit 52 through winding 69 of the high frequency transformer 85. So long as the device 47 is non-conductive the circuit 51 will not oscillate due to the increased negative bias impressed on the control members 63 and 64 of electric valves 57 and 58 through resistance 79 and resistances 77 and 78 respectively. This increased negative bias is due to the rectified low frequency current flowing through the resistance 81. However, if the device 47 is rendered conductive, thereby shunting the resistance 81, the negative bias voltage on the control members 63 and 64 will be decreased permitting the circuit 51 to oscillate at the frequency determined by the constants of the circuit.

As explained above in connection with the operation of the embodiment of my invention shown in Fig. 1, near the end of each half cycle of rectified alternating potential the self-biasing circuit for the control members 63 and 64 of electric valves 57 and 58 will render these valves non-conductive which in turn will interrupt the flow of current through electronic discharge device 47 for a length of time equal to or greater than the time of deionization for the particular valve used to permit the control member 50 to regain control.

The circuit for the rectified low frequency current supplied from alternating current circuit 53 during a half cycle comprises the upper portion of secondary winding 55 of transformer 54, conductor 71, primary winding 66 of transformer 65, conductor 73, electric valve 57, conductor 90, secondary winding 89 of transformer 88, conductor 84, resistance 81, and conductors 83 and 92. During the following half cycle of opposite polarity the rectified low frequency current will comprise the lower portion of secondary winding 55 of transformer 54, conductor 72, primary winding 67 of transformer 65, conductor 74, electric valve 58, conductor 91, secondary winding 89 of transformer 88, conductor 84, resistance 81 and conductors 83 and 92. Of course, when the electronic discharge device 47 is conductive permitting circuit 51 to oscillate, this device will effectively shunt the resistance 81 to by-pass the low frequency current through the device 47, secondary winding 87 of transformer 86, conductor 85, and the parallel circuit comprising resistance 82 and capacitance 83. The capacitance 75

83 will impress a negative potential on the anode 48 of electronic device 47 through the resistance 81 to effect deionization of the device and render it non-conductive at the end of each one half 5 cycle period of conduction of low frequency current.

Where it is desired to obtain periodic energization of the load circuit 52, a periodic control potential may be impressed on the control member 10 50 of electronic device 47 by means of the timing circuit 95. The timing circuit will periodically render electronic device 47 conductive to set the circuit 51 into oscillation to supply trains of high frequency oscillations to the load circuit 52. The 15 periods of energization and the intervals between the periods of energization of the load circuit 52 may be determined by choice of the constants for the timing circuit 95 and the setting of the adjustable contact 102.

20 By virtue of my invention, as illustrated by the embodiment described above, I provide arrangements for precisely and reliably controlling electric valve oscillators by means of electronic discharge devices of the gaseous type. I have found 25 that by means of my invention the voltages appearing across the control device are very much less than the control voltages which are involved when the prior art arrangements are used. For example, where the voltage appearing across the 30 secondary winding 55 of transformer 54 in Fig. 2 is approximately 2200 volts, the forward voltage appearing across the control valve 47 will be approximately 70 volts, whereas in the prior art arrangements the control device would be required to handle a voltage of approximately 770 35 volts.

While I have shown and described my invention as applied to a particular system of connections and as embodying various devices diagrammatically shown, it will be obvious to those skilled in the art that changes and modifications may be made without departing from my invention, and I, therefore, aim in the appended claims to cover 40 all such changes and modifications as fall within the true spirit and scope of my invention.

45 What I claim as new and desire to secure by Letters Patent of the United States is:

1. In combination, a source of pulsating unidirectional current, a load circuit, an oscillator circuit comprising an electric valve means interconnecting said source and said load circuit, and means for selectively rendering said oscillator circuit oscillatory and non-oscillatory in accordance with a decrease of said pulsating current 50 to a predetermined minimum value comprising an impedance element connected in said oscillator circuit, an electronic discharge device of the gaseous type connected across said impedance element for rendering said oscillator circuit oscillatory when in a conducting condition and non-oscillatory when in a non-conducting condition and a control circuit for rendering the discharge device conductive.

65 2. In combination, a source of pulsating unidirectional current, a load circuit, an oscillator circuit comprising an electric valve means interconnecting said source and said load circuit and means for selectively rendering said oscillator circuit oscillatory and non-oscillatory in accordance with a decrease of said pulsating current to a predetermined minimum value comprising an impedance element connected in said oscillator circuit for maintaining said circuit 70 non-oscillatory, an electronic discharge device

of the gaseous type connected in parallel with said impedance element for rendering said oscillator circuit oscillatory when in a conducting condition and non-oscillatory when in a non-conducting condition and a control circuit for rendering said electronic discharge device conductive. 5

3. In combination, a source of pulsating unidirectional potential, a load circuit, an oscillator circuit interconnecting said source and said load circuit comprising an electric valve means having a self-biasing control circuit, and means for selectively rendering said oscillator circuit oscillatory and non-oscillatory in accordance with a decrease of said pulsating potential to a predetermined minimum value comprising an impedance element connected in said oscillator circuit for maintaining said circuit non-oscillatory, an electronic discharge device connected in parallel with said impedance element for rendering said impedance element ineffective at predetermined intervals established by said source and a control circuit for rendering said electronic discharge device conductive. 20

25 4. In combination, a source of pulsating unidirectional potential, a load circuit, an oscillator circuit interconnecting said source and said load circuit comprising an electric valve means and a self-biasing control circuit therefor, and means for selectively rendering said oscillator circuit oscillatory and non-oscillatory in accordance with a decrease of said pulsating potential to a predetermined minimum value comprising an impedance element connected in said oscillator circuit for controlling said self-biasing control circuit for said electric valve means to render said electric valve means non-oscillatory, an electronic discharge device of the gaseous type connected in parallel with said impedance element for rendering said oscillator circuit oscillatory when in a conducting condition and non-oscillatory when in a non-conducting condition and a control circuit for rendering said electronic discharge device conducting. 30

35 5. In combination, a source of pulsating unidirectional potential, a load circuit, an oscillator circuit interconnecting said circuits comprising an electric valve means and a self-biasing control circuit for said electric valve means, an impedance element connected in the anode-cathode circuit of said electric valve means, and an electronic discharge device of the gaseous type connected across said impedance element for controlling said oscillator, said self-biasing control 40 circuit being arranged to render said electric valve means non-conductive for a period greater than the time of deionization of said electronic discharge device to permit said electronic discharge device to control said oscillator near the end of each pulsation of said unidirectional source. 45

6. In combination, a source of pulsating unidirectional potential, a load circuit, an oscillator circuit interconnecting said circuits comprising an electric valve having a control member and a self-biasing control circuit for said control member and arranged to render said electric valve non-conductive when said pulsating potential decreases to a value less than a predetermined critical value, impedance means connected in said oscillator circuit to maintain said valve non-conductive, and an electronic discharge device of the gaseous type connected across said means for controlling said oscillator circuit. 50

7. In combination, a source of pulsating unidirectional potential, a load circuit, an oscillator interconnecting said circuits comprising an electric valve having a control member and a self-biasing control circuit for said control member of said electric valve and arranged to render said electric valve non-conductive when said pulsating potential decreases to a value less than a predetermined critical value, an impedance device 10 for maintaining said valve non-conductive, and an electronic discharge device of the gaseous type connected in parallel with said impedance element for shunting said impedance element to render said impedance element ineffective at 15 predetermined intervals.
8. In combination, an alternating current circuit of relatively low frequency, a load circuit, means interconnecting said circuits comprising an electric valve oscillator circuit and a rectifier 20 energized from said alternating current circuit for supplying a pulsating unidirectional current to said oscillator, and means for selectively rendering said oscillator circuit oscillatory and non-oscillatory in accordance with a decrease of said 25 pulsating current to a predetermined minimum value comprising an impedance element connected in said oscillator circuit for controlling said oscillator, an electronic discharge device of the gaseous type connected across said impedance element for rendering said oscillator circuit oscillatory when in a conducting condition and non-oscillatory when in a non-conducting condition.
9. In combination, an alternating current circuit of relatively low frequency, a load circuit, means interconnecting said circuits comprising an electric valve oscillator circuit and a rectifier 30 energized from said alternating current circuit for supplying a pulsating unidirectional current to said oscillator circuit, means comprising an impedance element connected in said oscillator circuit for controlling said oscillator near the end of each unidirectional electrical impulse impressed upon the oscillator circuit by said rectifier, and an electronic discharge device of the 35 gaseous type connected across said impedance element for rendering said impedance element ineffective at predetermined intervals.
10. In combination, an alternating current 40 supply circuit, a load circuit, an electric valve circuit for rectifying each half cycle of the current of said alternating current circuit and for converting the energy thereof into high frequency oscillations, and an electronic discharge device of the gaseous type connected in the 45 anode-cathode circuit of said electric valve circuit for controlling said electric valve circuit.
11. In combination, a source of alternating current, a load circuit, an electric valve circuit 50 interconnecting said circuits for rectifying each half cycle of the current of said alternating current circuit and for converting the energy thereof into high frequency oscillations, an impedance element connected in the anode-cathode circuit 55 of said electric valve circuit for controlling said electric valve circuit, and an electronic discharge device of the gaseous type connected across said impedance element for controlling the effective impedance of said element in said electric valve 60 circuit.
12. In combination, an alternating current supply circuit of relatively low frequency, a load circuit, an electric valve circuit including electric valve means for rectifying each half cycle of the 65 current of said supply circuit and for converting 70 the energy thereof into high frequency oscillations to produce in said load circuit relatively high frequency electrical oscillations, a self biasing control circuit for said electric valve means for rendering said electric valve means non-conductive at the end of each electrical impulse, and means comprising an electronic device of the gaseous type connected in the anode-cathode circuit of said electric valve circuit for controlling said electric valve circuit. 75
13. In combination, an alternating current supply circuit, a load circuit, an oscillator circuit interconnecting said circuits for rectifying each half cycle of the current of said supply circuit and for converting the energy thereof into high frequency oscillations comprising an electric valve means, and means for controlling said electric valve means at the end of each half cycle of current supplied from said alternating current circuit in accordance with a decrease of the rectified current to a predetermined minimum value comprising an impedance element connected in said oscillator circuit for maintaining said electric valve means non-conductive, an electronic discharge device of the gaseous type connected across said impedance element for rendering said impedance element ineffective at predetermined intervals and a control circuit for rendering said electronic discharge device conductive. 80
14. In combination, an alternating current supply circuit, a load circuit, an oscillator circuit interconnecting said circuits for rectifying each half cycle of the current of said supply circuit and for converting the energy thereof into high frequency oscillations comprising electric valve means, an electronic discharge device of the gaseous type connected in said oscillator circuit for controlling said electric valve means, and means connected in the anode-cathode circuit of said electronic discharge device for controlling said electronic discharge device. 85
15. In combination, an alternating current supply circuit, a load circuit, an oscillator circuit interconnecting said circuits comprising electric valve means, a self-biasing control circuit for rendering said valve means non-conductive at the end of each half cycle of potential of said alternating current circuit, means connected in said oscillator circuit for maintaining said valve means non-conductive after said valve means has been rendered non-conductive by said control circuit, and an electronic discharge device of the gaseous type for rendering said last-mentioned means ineffective at predetermined intervals. 90
16. In combination, an alternating current supply circuit, a load circuit, an oscillator circuit interconnecting said circuits for rectifying each half cycle of the current of said supply circuit and for converting the energy thereof into high frequency oscillations comprising electric valve means, a self-biasing control circuit for rendering said valve means non-conductive at the end of each half cycle of potential of said alternating current circuit, an impedance means connected in said oscillator circuit for maintaining said electric valve means non-conductive after said electric valve means has been rendered non-conductive by said self-biasing control circuit, an electronic discharge device of the gaseous type connected across said impedance element for rendering said impedance element ineffective, and means comprising a parallel connected capacitance and resistance in the anode-cathode circuit of said electronic discharge device. 95

vice for controlling said electronic discharge device.

17. In combination, an alternating current supply circuit, an alternating current load circuit, electric translating apparatus for transmitting energy therebetween comprising a full wave rectifier including a pair of unidirectional conducting paths arranged to conduct current alternately, an electronic discharge device, of the type employing an ionizable medium and having a control member, connected in circuit with said unidirectional conducting paths for controlling the transfer of energy from said supply circuit to said load circuit, and means connected across said electronic discharge device for rendering said device nonconductive at the end of each half cycle of conduction to permit said control member to obtain control.

18. In combination, an alternating current supply circuit, an alternating current load circuit, electric translating apparatus connected

therebetween comprising an inductive winding having terminal connections and a connection electrically intermediate said terminal connections, a pair of electric valve means each connected in circuit with a different one of said terminal connections and arranged to transmit current alternately, an electronic discharge device of the type employing an ionizable medium and having a control member connected in circuit with said electric valve means and connected in circuit with said intermediate connection for controlling said electric valve means, a control circuit for energizing said control member, and means comprising a capacitance connected in series relation with said electronic discharge device and an impedance element connected across said capacitance and said electronic discharge device for rendering said device nonconductive at the end of each half cycle of conduction to permit said control member to obtain control.

HAROLD W. LORD.
